PIE CRUST ROLLING BOARD

Florentine Giard, 3845 Southwestern Blvd., Dallas, Tex.

Filed May 27, 1963, Ser. No. 75,069

Term of patent 14 years

(Cl. D44—1)

Fig. 1

I claim:

The ornamental design for a pie crust rolling board, substantially as shown.
